UNITED STATES PATENT OFFICE.

JOHN CLIFFORD WHITRIDGE, OF COLUMBUS, OHIO, ASSIGNOR TO THE BUCKEYE STEEL
CASTINGS COMPANY, OF COLUMBUS, OHIO.

CAR COUPLING.

Application filed March 22, 1923. Serial No. 626,972.

To all whom it may concern:

Be it known that I, JOHN CLIFFORD WHITRIDGE, a citizen of the United States, and a resident of Columbus, in the county of 5 Franklin and State of Ohio, have invented certain new and useful Improvements in Car Couplings; and I do hereby declare the following to be a full, clear, and exact description of the invention, such as will enable others skilled in the art to which it 10 pertains to make and use the same.

This invention relates to car couplings and has for its object the provision of means for connecting an automatic M. C. B. coupler with an European hook type coupler whereby variations in the heights of the cars will be accommodated and jamming of the parts when the cars come together will be avoided. The invention is illustrated in the 15 accompanying drawing and will be herein-after fully set forth.

In the drawing, Figure 1 is a plan view of the invention; Figure 2 is a side elevation.

A portion of a hook-type European coupler is shown at 1 and a typical M. C. B. automatic coupler is shown at 2. On the bottom of the drawhead of the coupler 2 I form the lugs or ears 3 to and between which is pivoted an end of a bar link 4 which is constructed at its outer end with a longitudinally extending slot 5 having an offset or notch 6 in its upper wall at its rear end. A loop link 7 is fitted over the hook coupler 1 and through the slot 5 to constitute a foldable slidable connection between the bar link and the hook coupler.

It will be readily noted that the arrangement of parts illustrated permits relative pivotal movement between each coupler and 40 the element attached thereto or engaged therewith so that the connection will readily accommodate itself to variations in the heights of the couplers. Should the cars come together, the links 4 and 7 will fold 45 downwardly about the engagement of the end of the loop 7 in the notch 6 and will assume a pendent position below and out of the way of the couplers. In connecting the

couplers, the link 7 may be engaged in the slot 5 at the front end thereof so that the 50 operator may the more easily engage the link with the hook coupler. Then upon movement of the cars toward each other, the links will slide on each other, and assume the normal position shown in Figure 2. It 55 will be understood, of course, that the links may be supported by the operator, either manually or with the aid of a suitable tool, until the link or loop 7 seats in the notch 6.

It will be seen that I have provided an exceeding simple structure which may be very easily applied at a low cost and will prove highly efficient in use.

Having fully described my invention what I claim as new and desire to secure by Letters Patent, is:—

1. In a device of the class described, the combination with a hook coupler, and an M. C. B. automatic coupler, of a bar link permanently pivoted at one end to the underside of the M. C. B. coupler and provided at its free end with a longitudinal slot, a loop link having one end engaged through the slot in the bar and its opposite end adapted to be engaged over the hook 70 coupler, and means for holding the links against relative endwise movement when the hook coupler is engaged.

2. In a device of the class described, the combination with a hook coupler, and an 80 M. C. B. automatic coupler, of a bar link pivoted at one end on the bottom of the M. C. B. coupler and provided at its free end with a longitudinal slot having a notch in its upper wall at its rear end, and a loop 85 link adapted to have one end engaged over the hook coupler and having its opposite end engaged in the longitudinal slot in the bar link.

In testimony whereof, I have signed this 90 specification in the presence of two subscribing witnesses.

JOHN CLIFFORD WHITRIDGE.

Witnesses:

JOHN S. MCPHERSON,

PAUL FRANKLIN.
